UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,202, dated March 29, 1881.

Application filed February 7, 1881. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a group composed of the figure J, consisting of roses supported on spreading leaves; of the figure I, a projecting branch bearing leaves and flowers; of the figure L, a rose with accompanying leaves and star-flowers; of the figure K, consisting of circular leaves and flowers, and of the figure M, a branching leafy spray.

D is a figure consisting of leaves and flowers spreading over a portion of the trellis-like figure O. This figure O consists of a band 25 bent at various angles, running irregularly through the design, and presenting the appearance of trellis-work.

The figure C consists of branching leaves, sprays, and circular flowers, supported by a 30 portion of the trellis O.

The group B consists of leaves, flowers, and branches extending over a portion of the trellis O, and contains the rose-like figure G, the rose-like spray H, and the figure E, composed 35 of flowers and leaves.

The whole effect is that of an angular trellis-work running irregularly through the de-

sign, and bearing upon it or connecting the various figures described.

I claim—

1. The design for carpets, consisting of the figure J, substantially as shown. 40
2. The design for carpets, consisting of the figure I, substantially as shown.
